DESIGN FOR A TABLE LAMP

James A. Richards and Norman C. Russell,
Kenosha, Wis.

Application July 3, 1948, Serial No. 147,368

Term of patent 3½ years

(Cl. D48—20)

To all whom it may concern:

Be it known that we, James A. Richards and Norman C. Russell, citizens of the United States and residents of Kenosha, in the county of Kenosha and State of Wisconsin, have invented a new, original, and ornamental Design for a Table Lamp, of which the following is a specification, reference being had to the accompanying drawing, forming a part thereof.

In the drawing:

Fig. 2 is a perspective view of the lamp as seen from one end thereof; and

Fig. 3 is a further perspective view of the lamp as seen from one corner thereof and looking down thereon.

We claim:

The ornamental design for a table lamp, substantially as shown.

JAMES A. RICHARDS.
NORMAN C. RUSSELL.
